WIRELESS TRANSMITTER

Application filed October 9, 1925, Serial No. 61,556, and in Great Britain October 13, 1924. Renewed February 18, 1931.

The present invention relates to an improved method and means for signaling by means of vacuum tube transmitters, and is particularly applicable to such transmitters when large power is employed and when it is required to transmit signals at high speed.

It is a further object of the invention to provide a method of controlling the amplitude of oscillations of transmitters of high power.

It is a further object of this invention to provide an adjustable means for controlling the amplitude of employed oscillations in a transmitting circuit in which high voltages are used in the transmitting device.

Other objects of the invention will appear from the following description of the invention taken in connection with the accompanying drawings in which:

Fig. 1 is a diagrammatic view of the circuits and triodes arranged according to the preferred form of the present invention; and,

Fig. 2 shows a modification of the invention shown in Fig. 1. Like letters and like characters are used throughout the specification and drawings to describe like parts of the circuits and apparatus.

Vacuum tube transmitters of high power are usually operated according to the so-called independent drive principle, that is, the main oscillatory power is generated by means of a number of vacuum tubes or triodes, the grids of which are excited from a low power vacuum tube (generally termed the independent drive).

It is also a well known practice to interpose an intermediate bank of vacuum tubes between the independent drive circuit and the main oscillator and to supply the anode voltage to both these banks of vacuum tubes from a common source of electrical power of high voltage.

Occasionally also the independent drive is supplied from the same source of power, but more commonly it is supplied from a separate source.

According to our present invention a resistance is inserted in the lead from the high voltage generator to the intermediate

amplifier vacuum tube anodes in such a position that the anode current of the intermediate amplifier or vacuum tube passes through this resistance but the anode current of the main amplifier does not. In addition, a vacuum tube or a number of vacuum tubes, hereinafter called the absorber, is connected in such a manner as to be in series with the resistance and across the source of high voltage, and means are provided for applying to the grid of the absorber either a positive or a negative potential as desired. It will thus be seen that with a suitable value of resistance and with the absorber of suitable current carrying capacity, when the grid of the absorber is made sufficiently positive the anode voltage of the intermediate amplifier will be reduced to a very small value, due to the voltage drop across the resistance, whereas, when the absorber grid is made negative, the voltage drop across the resistance or highly resistive impedance will only be that caused by the anode current of the intermediate amplifier, and consequently will not appreciably affect the normal operation of that circuit. This follows from the well-known properties of the usual vacuum tube. In this manner by applying the said potentials to the absorber grid by a signaling key or switch, the anode potential of the intermediate amplifier can be controlled, and in consequence the amplitude of the oscillations of the main amplifier will also be controlled.

According to the preferred embodiment of the invention shown in Fig. 1 of the drawings, D represents an independent drive, source of high frequency oscillations, generator of high frequency energy, or oscillator circuit coupled to the grid circuit of an intermediate amplifier or electron discharge device V1, the plate circuit of which is coupled to the grid circuit of the final amplifier or electron discharge device V2. A is an aerial which is energized by induction from the plate circuit of the amplifier V2. G is a generator supplying the plate potentials of the amplifiers V1 and V2, the latter directly, and the former through a resistance R1.

Connected across the resistance or an impedance of high resistance R1 and the generator G is an absorber comprising tube V3, batteries B1 and B2, resistance R2 and 5 modulating means in the form of switch K, which may conveniently be the usual type of telegraph key, arranged and connected as shown so that operation of the said switch K will apply modulating potentials to the 10 grid, or in other words, will change the potential of the grid of the tube V3 from positive to negative, or vice versa, as will be more fully explained below.

It will be apparent that when the grid 15 of vacuum tube V3 is positive, there will be a considerable drop of potential across the resistance R1, due to the current taken by the absorber circuit, and the potential applied to the plate or electrode of electron 20 discharge device V1 other than the usual grid and cathode thereof; or in other words, an electrode of electron discharge device V1 maintained at a higher potential than the usual grid and cathode thereof will therefore be considerably reduced. The switch 25 K, therefore, serves to control the output from the tube V1 and the amplitude of the oscillations of the main amplifier V2.

B3 is a battery connected in the grid lead 30 of the main amplifier V2, so as to apply a desired degree of negative bias in V2. This fixed negative bias is so chosen that when the absorber is rendered conductive and the oscillations of the intermediate amplifier are 35 thereby reduced to zero, the anode current of the main tube will cease, that is, the tube is normally biased to cut off, as is usual in operating power amplifiers.

It will be seen, therefore, that by suitably 40 proportioning the resistance and absorber any required fraction of the full direct current load may be taken from the high voltage source and used up in the resistance during the time the absorber grid is positive, at 45 which time the main amplifier takes no direct current, thus preventing voltage surges and variations in the direct current supply circuits when signaling.

In the description of the operation of 50 this device, we will first consider the case when the switch K is closed. Under these conditions the battery B1 impresses a negative potential upon the grid of the tube V3, thereby reducing the flow of current through 55 the resistance R1. This results in a small potential drop from the generator G to the plate of the tube V1, which therefore receives approximately its normal potential, thus enabling it to operate as an amplifier.

In the event, however, that it is desired 60 to reduce the degree of amplification, the switch is opened at K and due to the battery B2, the grid is positively charged and 65 there is a considerable flow of current

through the resistance R1, which in turn causes a substantial potential drop across this resistance and consequently a lower plate voltage in the tube V1. As a result of this condition, the action of the tube V1 70 as an amplifier is materially reduced and, in fact, may be reduced to zero.

According to the construction shown in Fig. 2 the absorber and its associated grid bias control means are replaced by a switch S of the necessary current carrying capacity. When the switch S is closed, the potential applied to the plate of the tube V1 is reduced in a manner made clear in connection with the description of Fig. 1 above, 75 owing to the resulting drop of potential 80 across the resistance R1.

While we have shown and described the use of a single vacuum tube electron discharge device or triode for each of the intermediate 85 and main amplifiers and also for the absorber, it will be understood that a bank of triodes or tubes may be used for this purpose, as is readily apparent to one skilled 90 in the art.

Having thus described our invention, we 95 claim and desire to secure by Letters Patent of the United States, the following:

1. In a signalling system, an oscillator, an amplifier having input and output circuits the input circuit of which is coupled to said oscillator, a second amplifier coupled to the output circuit of said first amplifier, said second amplifier having an output circuit, a single direct current source supplying 100 direct current to both amplifiers, an impedance between the source and the first amplifier only and a modulating device connected across said source and impedance.

2. In a signalling system, an amplifier 105 having input and output electrodes, means for impressing oscillations on the input electrodes, a circuit connecting the output electrodes and including a resistance and a current source serially connected, a variable 110 impedance connected across said source and said resistance, and telegraphic keying means for rendering said impedance either high or low, whereby when said impedance is low the voltage drop in said resistance 115 is high and the voltage across said output electrodes is substantially reduced.

3. In a signalling system, an amplifier 120 having input and output electrodes, means for impressing oscillations on the input electrodes, a circuit connecting the output electrodes and including a resistance and a current source serially connected, an electron 125 discharge device having its output circuit connected across said source and said resistance, a source of relatively positive potential, a source of relatively negative potential, and keying means for connecting either of said sources to a control electrode of the electron discharge device in order to

vary the flow of current through the resistance and thereby vary the potential applied to the amplifier.

4. A transmitter comprising a master oscillator, first and second electron emission tube amplifiers, a common source of direct anode potential for both of said amplifiers, a fixed impedance connected between the source and the tube anode of one of said amplifiers and a modulating circuit of variable impedance connected in shunt with the source and fixed impedance for varying the anode potential applied to one of the amplifiers and means for simultaneously and appropriately varying the anode current supplied to the other amplifier.

5. A transmitter comprising a master oscillator, an intermediate electron emission tube amplifier stage, a power amplifier stage, a common source of direct anode potential for both of said amplifier stages, a fixed impedance connected between the source and the tube anode of the intermediate amplifier stage, a modulator tube having its anode circuit in shunt with the source and fixed impedance, and modulating means for varying the potential of the control electrode of the modulator tube in order to vary the anode potential applied to the intermediate amplifier stage and means to simultaneously and appropriately vary the anode current supplied to the power amplifier stage.

6. A transmitter comprising a master oscillator, an intermediate electron emission tube amplifier stage, a power amplifier stage, means to negatively bias the power amplifier stage to cutoff, a common source of direct anode potential for both of said amplifier stages, a fixed impedance connected between the source and the tube anode of the intermediate amplifier stage, a modulator tube having its anode circuit connected in shunt with the source and fixed impedance, a source of relatively positive potential, a source of relatively negative potential, and a key for impressing either the positive or negative potential on the control electrode of the modulator tube according as the key is open or closed means controlled thereby for decreasing the anode potential of the intermediate amplifier during key open periods, and at the same time to absorb the direct anode current which normally flows through the power amplifier stage during the key closed periods.

7. In apparatus for electrical currents, an electron discharge device having an electron emitting cathode, a grid, and another electrode, a resistance connected at one end to said electrode and at another point to a potential terminal, an impedance coupled to said resistance, and means for varying the value of said impedance whereby the current flowing through said potential terminal and resistance is varied thereby varying by virtue

of the potential fall across said resistance, the potential on the electrode to which said resistance is connected.

8. In apparatus for electrical currents, an electron discharge device having an electron emitting cathode, a grid, and another electrode, a resistance connected at one end to said electrode and at its other end to a source of potential, an impedance comprising an electron discharge device coupled to said source of potential and resistance, and means for varying the current flow through said last mentioned electron discharge device and thereby the current flowing through said resistance whereby the potential on said electrode of said first mentioned electron discharge device is varied.

9. In a signaling system wherein high frequency undulatory energy is varied in accordance with relatively low frequency signaling energy, an electron discharge device having within an hermetically sealed envelope an electron emitting cathode, a grid, and another electrode maintained at a relatively higher potential than said grid and cathode; a resistance connected at one point to said electrode and at another point to a source of substantially unidirectional potential, an impedance associated with said resistance, a source of relatively high frequency energy coupled to said electron discharge device; and means for varying the value of said impedance in predetermined fashion whereby the current flowing through said resistance from said source of substantially unidirectional potential is varied, thereby varying by virtue of the fall of potential across said resistance, the potential on the electrode to which said resistance is connected.

10. In a signaling system wherein high frequency undulatory energy is varied in accordance with relatively low frequency signaling energy, an electron discharge device having within an hermetically sealed envelope an electron emitting cathode, a grid and another electrode maintained at a relatively higher potential than said grid and cathode; a resistance connected at one point to said electrode and at another point to a source of substantially unidirectional potential, an impedance associated with said resistance, a source of relatively high frequency energy coupled to said electron discharge device; means for varying the value of said impedance in predetermined fashion whereby the current flowing through said resistance from said source of substantially unidirectional potential is varied, thereby varying by virtue of the fall of potential across said resistance, the potential on the electrode to which said resistance is connected.

11. In apparatus for electrical currents, an electron discharge device having an electron emitting cathode, a grid, and another electrode, a resistance connected at one end to said electrode and at another point to a potential terminal, an impedance coupled to said resistance, and means for varying the value of said impedance whereby the current flowing through said potential terminal and resistance is varied thereby varying by virtue of the fall of potential across said resistance, the potential on the electrode to which said resistance is connected; an amplifier associated with said electron discharge device for amplifying modulated high frequency energy therefrom, said amplifier comprising an evacuated con-

tainer having therein an electron emitting cathode, a control electrode, and another electrode maintained at a potential relatively higher than the other electrodes of said amplifier; and, a connection from said source of substantially unidirectional potential to an electrode of said amplifier for suitably polarizing said last mentioned electrode.

11. In a signaling system utilizing propagated electromagnetic wave energy derived from the flow of modulated high frequency currents, the combination of an electron discharge device having an hermetically sealed container wherein are contained an electron emitting cathode, a grid, and another electrode maintained at a substantially unidirectional potential higher than said grid and cathode; a resistance connected at one point to said electrode and at another point to a source of substantially unidirectional potential, an impedance comprising an electron discharge device associated with said source of potential and resistance; and, means for varying in predetermined fashion the current flow through said last mentioned electron discharge device and thereby the current flowing through said resistance whereby the potential on said electrode of said first mentioned electron discharge device is varied.

12. In a signaling system utilizing propagated electromagnetic wave energy derived from the flow of modulated high frequency currents, the combination of an electron discharge device having an hermetically sealed container wherein are contained an electron emitting cathode, a grid, and another electrode maintained at a substantially unidirectional potential higher than said grid and cathode; a resistance connected at one point to said electrode and at another point to a source of substantially unidirectional potential, an impedance comprising an electron discharge device associated with said source of potential and resistance; means for varying in predetermined fashion the current flow through said last mentioned electron discharge device and thereby the current flowing through said resistance whereby the potential on said electrode of said first mentioned electron discharge device is varied; a source of high frequency oscillatory electrical energy coupled to the input side of said first mentioned electron discharge device; an amplifier comprising an evacuated container having therein input electrodes and another electrode maintained at a higher positive potential than any one of said input electrodes, means for subjecting said input electrodes to high frequency electrical oscillations, a circuit connecting said electrode maintained at a higher positive potential and one of said input electrodes including a resistance and a current source serially connected, another electron discharge device having its output circuit associated with said source and said resistance, a source of modulating potentials, and means for varying the current flow through said resistance in accordance with said modulating potentials whereby the flow of current through the resistance is

absence of currents to be amplified from said first mentioned electron discharge device, the unidirectional current flow through said amplifier is reduced.

13. In a communication system wherein electromagnetic wave energy is propagated through space by virtue of the flow of signal modulated high frequency undulatory electrical energy, a source of high frequency electrical oscillations; an electron discharge device having input and output circuits, the input circuit of which is coupled to said source; an electron discharge device amplifier coupled to the output circuit of said first mentioned electron discharge device, said amplifier having an output circuit, a source of substantially unidirectional potential supplying potential to an electrode of said first mentioned electron discharge device; a resistance between said source and electrode; modulating means connected across said source and said resistance whereby the potential on said electrode is varied upon actuation of said modulating means; and a connection from said source to an electrode of said amplifier for polarizing the electrode so connected.

14. In a communication system wherein electromagnetic wave energy is propagated through space by virtue of the flow of signal modulated undulatory electrical currents, an amplifier having input electrodes and another electrode; means for impressing high frequency undulatory electrical energy on the input electrodes, a circuit connecting said other electrode of said device and one of the input electrodes thereof comprising a resistance and a unidirectional current source serially connected; and, modulating means associated with said resistance for varying the current flow therein and thereby the potential applied to said other electrode to which said resistance is connected.

15. In a communication system utilizing propagated electromagnetic wave energy derived from the flow of signal modulated high frequency undulatory electrical currents, an electron discharge device comprising an evacuated container having therein input electrodes and another electrode maintained at a higher positive potential than any one of said input electrodes, means for subjecting said input electrodes to high frequency electrical oscillations, a circuit connecting said electrode maintained at a higher positive potential and one of said input electrodes including a resistance and a current source serially connected, another electron discharge device having its output circuit associated with said source and said resistance, a source of modulating potentials, and means for varying the current flow through said resistance in accordance with said modulating potentials whereby the flow of current through the resistance is

varied thereby varying the potential applied to said electrode maintained at a relatively high positive potential.

16. In a communication system utilizing propagated electromagnetic wave energy derived from the flow of signal modulated high frequency undulatory electrical currents, an electron discharge device comprising an hermetically sealed container where-
5 in are contained a cathode, and a plurality of cold electrodes; an output circuit for said device; an input circuit for said device, means for subjecting a pair of electrodes of said devices to high frequency undulatory electrical potentials, and means for modu-
10 lating the electrical potentials to which said electrodes are subjected comprising a source of substantially unidirectional electrical potential, a resistance in series therewith and
15 in series with an electrode of said electron discharge device; and means for varying the current flow through said resistance in predetermined fashion, whereby the potential on the electrode to which said resistance
20 is connected is varied in accordance with the predetermined variations in current flow through said resistance.
17. In a communication system utilizing propagated electromagnetic wave energy de-
25 rived from the flow of signal modulated high frequency undulatory electrical currents, an electron discharge device comprising an hermetically sealed container having therein a cathode and a plurality of cold
30 electrodes; a circuit connected across said cathode and one of said cold electrodes, a circuit connected across said cathode and another cold electrode, said cathode and one of said cold electrodes being subjected
35 to high frequency potentials whereby high frequency energy appears in one of said circuits; and, means for producing modu-
40 lation in the high frequency energy appearing in one of said circuits, comprising a re-
45 sistance and a source of substantially uni-
50 directional potential connected in series with one of said cold electrodes and an electron discharge device associated with said
55 resistance and source to produce in pre-
determined fashion changes in current flow through said resistance whereby the potential on said electrode connected in series with said resistance and source of potential is varied thereby producing modulation in high frequency currents appearing in said circuit.
18. In a communication system utilizing propagated electromagnetic wave energy de-
60 rived from the flow of signal modulated high frequency undulatory electrical currents, a transmitting arrangement comprising a source of high frequency currents, first and second electron discharge devices
65 coupled thereto, a common source of direct potential for an electrode in each of said electron discharge devices, a fixed impedance connected between the source and an electrode of one of said devices and a modulating circuit of variable impedance associated with the source and fixed impedance for varying the potential applied to the electrode of one of said devices connected with said source and impedance.
19. In a communication system utilizing propagated electromagnetic wave energy de-
70 rived from the flow of signal modulated high frequency undulatory electrical currents, a transmitting arrangement comprising a source of high frequency currents, first and second electron discharge devices coupled thereto, a common source of direct anode potential for both of said devices, an impedance connected between the source and the anode of one of said devices, a modulating circuit of variable impedance connected in shunt with the source and said impedance for varying the anode potential applied to one of the devices; and means for polarizing the other of said devices whereby in the absence of high frequency currents in the output circuit of said one of said devices, the unidirectional current flow through said other device is reduced.
20. In a system utilizing propagated elec-
75 tro-magnetic waves derived from the flow of signal modulated high frequency undulatory electrical currents, a source of high frequency potential, first and second electron emission tube amplifiers, a common source of direct anode potential for both of said amplifiers, an impedance connected between the source and the tube anode of one of said amplifiers, and, a modulating circuit of vari-
80 able impedance connected in shunt with the source and impedance for varying the potential applied to one of said amplifiers.
21. In a system utilizing propagated elec-
85 tro-magnetic waves derived from the flow of signal modulated high frequency undulatory electrical currents, a transmitting ar-
90 rangement comprising a source of high frequency potentials, first and second electron discharge device amplifiers, a common source of positive potential for an electrode in each of said amplifiers, a resistance connected be-
95 tween the source and an electrode of one of said amplifiers, and, a modulating circuit of variable impedance connected across the source and resistance for varying the potential applied to the electrode to which said resistance is connected.
22. In a system utilizing propagated elec-
100 tromagnetic waves derived from the flow of signal modulated high frequency undulatory electrical currents, a transmitting ar-
105 rangement comprising a source of high frequency oscillations, an intermediate electron emission tube amplifier stage, an amplifier
110
- 115
- 120
- 125

stage following the intermediate stage, means to negatively bias the stage following the intermediate stage substantially to cut off, a common source of direct anode potential for both of said stages, an impedance connected between the source and the tube anode of the intermediate stage, a modulator tube having its anode circuit connected to said source and impedance, a source of modulating potentials, and means for impressing the modulating potentials on the control electrode of the modulator tube whereby the current flow through said impedance is varied thereby modulating the high frequency energy fed to the stage following said intermediate amplifier stage.

23. In a system wherein intelligence is transmitted by electromagnetic waves derived from the flow of high frequency undulatory currents operated upon in accordance with the intelligence to be transmitted, an electron discharge device having within an hermetically sealed container an electron emitting cathode and a plurality of cold electrodes, a resistance and a source of potential connected in series between said electron emitting cathode and one of said cold electrodes, means for causing currents to flow through said resistance in accordance with intelligence to be transmitted, another electron discharge device having an evacuated container wherein are contained an electron emitting cathode and a plurality of cold electrodes, an output circuit connected to output electrodes of said second mentioned electron discharge device, means for subjecting input electrodes of said second mentioned electron discharge device to high frequency potentials, whereby high frequency energy appears in said output circuit, and, a connection from said resistance to a cold electrode of said second mentioned electron discharge device for varying the flow of high frequency energy in said output circuit in accordance with the current flow through said resistance.

24. In a system for transmitting intelligence, a master oscillator for generating high frequency oscillations, an amplifier coupled to said oscillator for amplifying the oscillations generated thereby, said amplifier comprising an hermetically sealed container wherein are contained an electron emitting cathode and a plurality of cold electrodes, an output circuit coupled to output electrodes of said amplifier; a vacuum tube having within an evacuated container an anode, a cathode and a grid, a resistance and a source of potential serially connected between said anode and cathode, means coupled to the grid and cathode of said vacuum tube for varying the current flow through said resistance, and, a connection from said resistance to one of the cold electrodes of

said amplifier, for varying the high frequency oscillatory energy appearing in the output circuit of said amplifier.
